Application July 2, 1958, Serial No. 746,273

11 Claims. (Cl. 338—130)

This invention relates to a precision potentiometer capable of continuous rotation at relatively high speed.

Whereas the conventional Kelvin-Varley potentiometer is quite adequate for precision purposes in the laboratory where switching is performed manually, it is entirely unadapted for uses involving continuous rotation, continuous balance, automatic systems, or high speed operation.

It is accordingly among the objects of this invention to satisfy the need for a high speed continuously rotatable precision potentiometer incorporating certain of the Kelvin-Varley principles and further characterized by its: high degree of linearity, adaptability for use with direct or alternating current over a wide frequency range without phase shift; small size; low operating torque; lack of mechanical stops and clutches; and light weight.

A potentiometer conforming to the present invention comprises a pair of input terminals, similar banks of series resistors adapted to be connected in circuit across these terminals, the resistors of each bank having terminals arranged in an arc, a pair of segmental variable resistors having terminals defining opposed gaps, brushes for sequentially connecting the terminals of each segmental resistor to pairs of terminals of the resistor banks respectively, a wiper having an effective span exceeding the width of each of said gaps sequentially contacting the segmental resistors, switching means periodically interrupting the circuit between the input terminals and one of the banks, and driving means for imparting synchronous movements to the brushes, wiper and switching means. The driving means is preferably rotatable continuously through an arc exceeding 360°, and the brushes, wiper and switching means are likewise preferably rotatable. The switching means may include a pair of switches connected in parallel and driven at dissimilar speeds. One of the switches may be driven at the same speed as the wiper, and the other at the speed of the brushes. Reduction gearing is provided for rotating the wiper and brushes at dissimilar speeds, described herein as having a ratio of ten to one.

A more complete understanding of the invention will follow from a description of the accompanying drawings wherein:

Fig. 1 is a circuit diagram of an arrangement embodying the invention;

Fig. 2 is a circuit diagram depicting the positions assumed by the parts of Fig. 1 after the driving shaft has advanced one-half turn;

Fig. 3 is a circuit diagram depicting the positions assumed by the parts of Fig. 1 after the driving shaft has advanced nine and one-half turns;

Fig. 4 is an exploded perspective view of the parts of a potentiometer according to the present invention;

Figs. 5, 6 and 7 are plan views of commutator cards employed;

Figs. 8 and 9 are perspective views of brush assemblies which cooperate with the commutator cards;

Fig. 10 is a perspective view of one of the fixed resistors; and

Fig. 11 is an elevation of an assembled potentiometer.

As will appear from Fig. 1 of the drawings, each of 5 two resistor banks 20 and 22 is made up of eleven resistors connected in series, each bank including ten resistors 24 each having a value of $2r$ and one resistor 26 having a value of r . The resistor banks 20 and 22 are connected in parallel across a pair of input terminals 28 and 30, 10 a pair of parallel switches 32 and 34 being interposed between one input terminal 30 and the resistor bank 22. The resistors 24 are provided with terminals lettered A to K for the bank 20, and O to Y for the bank 22. Whereas each of the groups of terminals A to K and O to Y is 15 actually arranged in an annular fashion, they have been depicted in developed form in Figs. 1 to 3.

A vernier potentiometer 36 cooperating with the resistor banks, is composed of two helically wound sections 38 and 40, each extending through an arc of 20 slightly less than 180°, and a rotatable wiper 42 adapted to tap the turns of these sections and of sufficient width to bridge the gaps defined between the two sections. The sections 38 and 40 are adjusted to a precise value of $2r$ each by means of parallel connected trimmer resistors 44 25 and 46 respectively. The terminals 48 and 50 of the section 38 of the potentiometer are connected through a pair of slip rings 52 and 54 to a pair of brushes 56 and 58 respectively, which sequentially engage the terminals A to K of the resistor bank 20. As shown in Fig. 1, the brushes 56 and 58 are in contact with the terminals A and B respectively, while in Fig. 3 they have advanced to engage the terminals J and K, also respectively. In a similar manner, terminals 60 and 62 of the section 40 of the potentiometer are connected through a pair of slip rings 64 and 66 to a pair of brushes 68 and 70, respectively, which wipe over the terminals O to Y of the 35 resistor bank 22.

Disregarding the effects of the potentiometer sections 38 and 40, the total series resistance of each of the 40 resistor banks 20 and 22 is $21r$, since each contains ten resistors 24 having a value of $2r$ and one resistor 26 having a value of r . However, each winding section 38 and 40 also has a resistance of value of $2r$ so that when the brushes of these sections are bridging a fixed resistor 24 of its respective bank, the total effective resistance of each bank is $20r$. Thus, at any given instant, the current flowing in each bank of resistors will be the same, and the voltage drop across the terminals A and B under the conditions depicted in Fig. 1 where the effective resistance is r will be the same as across the terminals 28 and O of the bank 22 where the effective resistance of the uppermost resistor 26 is also r . Since the terminal B of the bank 20 is at the same potential as the terminal O of the bank 22, if the brush or wiper 42 moves counterclockwise from its position bridging the upper gap between the sections 38 and 40 as depicted in Fig. 1, it will 45 interpolate the resistor having terminals A and B while the brushes 56 and 58 are moving over these terminals respectively. By properly synchronizing the movements of these brushes 56 and 58 with that of the wiper 42, the brushes will reach the forward (lower in Fig. 1) edges of these terminals A and B at the same time the wiper 42 completes a half turn to a position in which it bridges the lower gap existing between the terminals 50 and 62 of the sections 38 and 40 respectively, as shown in Fig. 2. 50 While these movements have been occurring, the brushes 70 and 68, synchronized for movement at the same rate as the brushes 56 and 58, have traveled from their positions contacting the terminals X and Y in Fig. 1 to the 55 positions in contact with the terminals O and P as shown in Fig. 2.

Assuming the input voltage applied across the terminals

28 and 30 to have the value e , the potential difference between the terminals 30 and A will be $.95e$ and that between the terminals 30 and O will likewise be $.95e$. Hence, the same potentials will exist at the terminals 50 and 62 of the two sections bridged by the wiper 42 in Fig. 2 so that when the wiper moves farther in its counterclockwise rotation to break its contact with the section 38 there will be no flow of current nor production of transients.

Then as the wiper 42 proceeds to scan the turns of the section 40 it will interpolate values between $.95e$ and $.90e$ until it once again bridges the upper gap between the terminals 48 and 60 of the sections 38 and 40. By this time the brush 56 will have moved into contact with the terminal B whose potential is now .90E corresponding to that at the terminals P and 60. In this fashion, the output potential between the output terminals 72 and 74 will be derived alternately from the resistor banks 20 and 22 to produce linear values in a continuous fashion. The relative positions of the brushes after movement of the wiper 42 through nine and one-half turns, as compared with Fig. 1, has been depicted in Fig. 3, where the wiper 42 is about to interpolate between the values $.05e$ and zero, during which the brushes 56, 58, 68 and 70 will return to the positions which they previously assumed in Fig. 1. It will be clear, of course, that the direction of rotation can be continuous or may be changed if desired.

The wiper 42 is driven direct by a shaft 76, depicted by a broken line in Fig. 1. Suitable reduction gearing 78, likewise driven by the shaft 76, imparts one revolution to the brushes 56, 58, 68 and 70 for each ten of the wiper 42 through suitable shafting depicted by broken lines 80 and 32 in Fig. 1.

Also driven at one-tenth the speed of the wiper 42 through the 10:1 reduction gearing 78 and shafting represented in Fig. 1 by broken lines 84 and 86, are the rotary brushes 88 and 90 of the switches 32 and 34 respectively. The switch 32 includes a 360° inner slip ring 92 and an outer segmental slip ring 94 extending through an arc of approximately $179\frac{1}{2}^\circ$, and its brush 88 synchronized with respect to the wiper 42 so as to open the circuit between the slip rings 92 and 94 during slightly more than one-half of a revolution of the wiper 42. The switch 34 includes a 360° outer slip ring 96 and a segmental inner slip ring 98 extending through an arc of approximately 342° , and a brush 90 driven through the reduction gearing 78 in synchronism with the brush 88 to control the circuit between its slip rings 96 and 98. The timing is such that the circuit between the slip rings 96 and 98 is interrupted once during each ten turns of the wiper 42 when the brush 68 is in contact with its terminal Y and the brush 56 is just about to contact its terminal A. Were the switch 34 not open at this time, with the wiper 42 bridging the gap between the terminals 48 and 60, a short circuit across the input terminals 28 and 30 would occur, from the terminal 28, terminal A, brush 56, terminal 48, wiper 42, terminal 60 brush 68 and terminal Y to the terminal 30. The switch 32, driven at the same rate as the wiper 42, is connected in parallel with the switch 34 as further assurance against such short circuiting. Except for the transition period during which the circuit is to be interrupted, the switch 34 remains closed so that the switch 32 is rendered ineffective to open the circuit. However, should errors be present that would be multiplied by the switch 34 because of its reduced rate of rotation, the circuit would be interrupted by the switch 32 during the proper period.

The physical arrangement of the various components has been illustrated in Figs. 4 to 11. An insulating disk 100 shown in Fig. 6 carries the slip rings 52, 54 and 98 and the terminals A to K inclusive. As clearly shown, the terminal A is partially coextensive arcuately with the terminal K disposed radially outwardly therefrom, for cooperation with their brushes 56 and 58 shown in Fig. 8

where it will be evident that one set of these brushes is arcuately displaced from the other by an angle of approximately 36° . As shown in Fig. 4, the terminals A to K are connected to their fixed resistors by means of leads 102 extending through the disk 100.

Similarly, an insulating disk 104 depicted in Fig. 7, carries the slip rings 64, 66 and 98 and the terminals O to Y inclusive. In this case the terminals O and Y are partially coextensive and radially displaced, as are the terminals A and K of the disk 100, for cooperation with their similarly displaced brushes 68 and 70.

As will be noted from Figs. 6 and 7, the terminals F and T are divided to form radially displaced segments F and F_1 on the one hand, and T and T_1 on the other, bridged by jumpers 106. Should it be desirable to operate the potentiometer at one-half input potential, the jumpers 106 can be removed and suitable connection can be made from these segments to center tap terminals 108 and 110 shown in Fig. 4.

As clearly shown in Fig. 8, the brushes 68 and 70 are supported by an insulating block 112 having a shaft 114 for rotary contact with their slip rings 64 and 66 respectively, and the terminals O to Y of the resistor bank 22. Similarly, the block 112 supports the brushes 56 and 58 for rotary contact with their slip rings 52 and 54 respectively, and the terminals A to K of the resistor bank 20. As will be evident from Fig. 4, the block 112 is interposed between the disks 100 and 104 for switching engagement with the terminals and slip rings of both. The block 112 also carries the brushes 90 for cooperation with the slip rings 96 and 98 supported by the disks 104 and 100 respectively.

Another insulating disk 116 depicted in Fig. 5 carries a slip ring 118 connected to the output terminal 72, whose brush 120 establishes a connection to the wiper 42. This disk also carries the slip rings 92 and 94. The brush carrier 122 shown in Fig. 9 supports the wiper 42 and brushes 88 and 120 for cooperation with the slip rings carried by the disk 116 and the two sections 38 and 40 of the vernier potentiometer 36.

In its assembled form as depicted in Fig. 11, the device is housed in a cylindrical casing 126 to which a terminal block 128 is suitably fastened for supporting pins defining the terminals 28, 30, 72, 74, 108 and 110. The resistors 24 are wound on rectangular cores 130 in bifilar fashion, as shown in Fig. 10, and arranged radially as shown in Fig. 4, their leads 102 extending to their respective terminals A to K of the resistor bank 20 and O to Y of the resistor bank 22.

The shaft 114 carrying the insulating block 112 extends through a central opening 132 of the disk 104 to receive a spur gear 134 which is secured thereto for engagement with the teeth of the smaller gear 135 of a unitary pair, the larger gear 136 of the pair being rotatably supported on a shaft 138 carried by a plate 139 to which the disk 116 is secured. The drive shaft 76 carrying the block or brush carrier 122 terminates in a small gear 140 which projects through a central opening 142 of the disk 116 for engagement with the teeth of the larger gear 136. Threaded openings 144 formed in the plate 139 receive the ends of rods 146 which project through openings formed in the disks 100 and 104 to assure their proper relative positions after assembly. A cover member 148 containing an opening 150 through which the shaft 76 projects, houses the vernier potentiometer sections 38 and 40 and is suitably secured to the casing 126.

Whereas the invention has been described with respect to a single embodiment for purposes of illustration, it is not intended to be limited thereto beyond the scope of the appended claims.

I claim:

1. A potentiometer comprising a pair of input terminals, similar banks of series resistors, each bank being connected in circuit across said input terminals, said resistors of each bank having terminals arranged in an arc, a pair of segmental variable resistors having terminals

defining opposed gaps, brushes for sequentially connecting the terminals of each of said segmental resistors to pairs of terminals of said resistor banks respectively, a wiper having an effective span exceeding each of said gaps sequentially contacting said segmental resistors, switching means periodically interrupting the circuit between said input terminals and one of said banks, and driving means for imparting synchronous movements to said brushes, wiper and switching means.

2. A potentiometer as set forth in claim 1 wherein said driving means is rotatable.

3. A potentiometer as set forth in claim 1 wherein said driving means includes a shaft rotatable through an arc exceeding 360°.

4. A potentiometer as set forth in claim 1 wherein said switching means is rotatable.

5. A potentiometer as set forth in claim 1 wherein said switching means includes a pair of switches connected in parallel and driven at dissimilar speeds.

6. A potentiometer as set forth in claim 1 wherein said driving means includes reduction gearing for rotating said brushes and wiper at different speeds.

7. A potentiometer as set forth in claim 1 wherein said driving means includes reduction gearing for rotating said wiper and switching means at different speeds.

8. A potentiometer comprising a pair of input terminals, a pair of banks of resistors adapted to be connected in parallel with said input terminals, each bank containing a like number of resistors of equal value connected in series, taps from the resistors of each bank

10

15

being annularly disposed, a pair of vernier resistor segments, said segments being annularly disposed with gaps between adjacent segments, each segment having a resistance value equal to that of each said resistor of said banks, each segment having brushes adapted to contact adjacent pairs of taps of one of said banks, a wiper having an effective width greater than each of said gaps adapted to scan each of said segments sequentially, a rotary switch interposed in circuit between said input terminals and one of said banks, and driving means connected with said brushes, wiper and switch for effecting synchronous movement thereof.

9. A potentiometer as set forth in claim 8 wherein said brushes and wiper are so synchronized that adjacent terminals defining each gap between said segments are at equal potential each time said wiper assumes a gap bridging position.

10. A potentiometer as set forth in claim 8 wherein said annularly disposed taps are carried on proximate surfaces of spaced supports, and said brushes for both banks are interposed between said supports.

11. A potentiometer as set forth in claim 8 wherein said brushes, wiper and switch are continuously rotatable.
